(**) Term: **14 Years**

(57) **CLAIM**

The ornamental design for a graphical user interface for smart card-driven applications for a computer monitor and display screen, as shown and described.

(21) Appl. No.: **29/141,273**

DESCRIPTION

(22) Filed: **May 2, 2001**

The single FIGURE is a front view of a graphical user interface for smart card-driven applications for a computer monitor and display screen. The broken line drawing of a computer monitor and display screen is for illustrative purposes only and forms no part of the claimed design.
